(57) **CLAIM**

We claim the ornamental design for the handheld bottle sleeve, as shown and described.

DESCRIPTION

FIG. 1 is a perspective view of the handheld bottle sleeve, showing our new design.

FIG. 2 is a front view of the handheld bottle sleeve.

FIG. 3 is a left side view of the handheld bottle sleeve.

FIG. 4 is a right side view of the handheld bottle sleeve.

FIG. 5 is a rear view of the handheld bottle sleeve.

FIG. 6 is a top view of the handheld bottle sleeve.

FIG. 7 is a bottom view of the handheld bottle sleeve.

FIG. 8 is a top view of the handheld bottle sleeve showing an environment incorporating a collar tab illustrated in phantom lines, in which the other views of the collar tab are unornamented and further in which the remainder of the handheld bottle sleeve is as illustrated in FIGS. 1-7; and,

FIG. 9 is a top view of the handheld bottle sleeve showing an alternate environment incorporating an alternate collar tab illustrated in phantom lines, in which the other views of the collar tab are unornamented and further in which the remainder of the handheld bottle sleeve is as illustrated in FIGS. 1-7. Features illustrated in phantom lines are intended to show a preferred environment for the handheld bottle sleeve and form no portion of the claimed invention. As illustrated, an exemplary bottle, bottle cap, zipper, zipper pull, logo tag, and ventilation hole pattern are illustrated in phantom lines and therefore form no part of the claimed invention. The handheld bottle sleeve is formed from a flexible material that can expand to accommodate a bottle of different sizes and shapes other than the shape of the particular bottle as illustrated within the handheld bottle sleeve, and therefore the bottle as illustrated depicts a preferred environment for the handheld bottle sleeve.
